[57] CLAIM

The ornamental design for a ground fault circuit interrupter, as shown and described.

DESCRIPTION

FIG. 1 is a rear and left side perspective view of a ground fault circuit interrupter showing my new design;

FIG. 2 is a front and right side perspective view of the ground fault circuit interrupter shown in FIG. 1;

FIG. 3 is a rear view of the ground fault circuit interrupter shown in FIG. 1;

FIG. 4 is a left side view of the ground fault circuit interrupter shown in FIG. 1;

FIG. 5 is a front view of the ground fault circuit interrupter shown in FIG. 1;

FIG. 6 is a top view of the ground fault circuit interrupter shown in FIG. 1; and,

FIG. 7 is a bottom view of the ground fault circuit interrupter shown in FIG. 1.

The broken lines in FIGS. 1-5 are illustrated to show the environment only and form no part of the claimed design.
